UNITED STATES PATENT OFFICE.

FRANK C. PARSONS, OF EAST CLEVELAND, OHIO, ASSIGNOR TO THE STRONG, CARLISLE AND HAMMOND COMPANY, OF CLEVELAND, OHIO, A CORPORATION OF OHIO.

FURNACE.

1,132,681.

Specification of Letters Patent. Patented Mar. 23, 1915.

Application filed June 24, 1913. Serial No. 775,492.

To all whom it may concern:

Be it known that I, FRANK C. PARSONS, a citizen of the United States, and a resident of East Cleveland, county of Cuyahoga, and State of Ohio, have invented a new and useful Improvement in Furnaces, of which the following is a specification, the principle of the invention being herein explained and the best mode in which I have 10 contemplated applying that principle, so as to distinguish it from other inventions.

The subject of the present invention is a case hardening or annealing furnace of the "underfired" type which has been designed 15 to permit of an efficient and convenient operation. Extremely good results are also obtained by reason of the perfect sealing or closure of the combustion or heating chamber.

20 It has heretofore been impossible to design an annealing furnace in which the holders for the material were entirely removable from the furnace by reason of the lack of any suitable means for sealing the 25 space between such holders and the sides of the furnace when the holders were in position.

In the present invention I have provided 30 a removable truck or work holder which may be sealed against the sides of the furnace when the holders were in position.

In the present invention I have provided a removable truck or work holder which may be sealed against the sides of the furnace when in position, thus preventing the escape of any of the hot gases or the inlet 35 of any excess air from the outside.

To the accomplishment of these and related ends said invention then consists of 40 the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

Figure 1 is a front elevation, partly in section, of my improved furnace; Fig. 2 is 50 a side elevation partially in section, and Fig. 3 is a partial section showing a modified construction.

In Fig. 1 the furnace may be seen to consist of a suitable chamber 1 which is closed 55 at all points except for a removable door 2

at one end, such door being lifted by any suitable means. Into this chamber there may be moved a truck 3 provided with wheels 4 engaging upon a track 5 mounted in the bottom of the furnace. The position 60 of the burners 6 for heating the furnace chamber is relatively unimportant as they may be placed in the furnace walls 7 as in Fig. 1, or in the main floor 8 of the trucks as shown in Fig. 3. If placed in the position 65 shown in Fig. 1 the burners will be suitably connected by means of pipes 9 and 10 with an air and gas supply. If mounted on the truck the connections will be similar, consisting of pipes 11 and 12, but it will be 70 necessary to provide a flexible connection between the main supply pipe and a pipe which is mounted in the rear of the furnace wall. This connection must therefore be 75 broken upon each removal of the truck from the furnace.

The truck is provided with a main floor 8 composed of suitable refractory material such as fire-brick, and above the main floor there will be mounted a second or supplementary floor 15, thus forming a combustion chamber between the main and secondary floors. The burners 6 in the walls of the furnace will be disposed at such a level that they will discharge directly into 85 the space between the two floors. The floors are so spaced that a combustion chamber is formed between them. The material which is being treated will, of course, be carried upon the second floor and thus it 90 will be heated from all sides. The furnace chamber thus formed will be heated on all sides by the burning gas, particularly on the sides and floor and the materials will be heated by heat radiated from these parts. 95 In this way all direct heating of the material is eliminated, that is, the gas flame is not allowed to be directed against the material. The advantage of this result is an even and effective treatment of the objects 100 being heated, together with a very good heating efficiency of the furnace.

Upon the sides of the truck and at the same level upon the sides of the furnace there are mounted inclined or beveled plates 16 and 17 which are adapted to be contacted throughout their length by pivotally mounted bars 18, such bars being supported upon rods 19 pivotally attached to the bottom of the furnace chamber. It will be obvious that 110

bars of various shapes may be used as square bars are not the only kind which will serve the purpose. These bars 18 are hollow and are connected at either end with a flexible tube 20 which will be attached to some suitable source of water supply for the purpose of keeping the tubes cool and preventing their becoming so heated that they will warp or scale, in which event the closure would be imperfect. In this way the space above the main floor of the truck is completely sealed from the bottom of the furnace and also from the outside air. The bars 18 are brought into position and maintained there-
15 in by weights 25 connected by chains 26 ex- tending over sheaves 27.

The truck is constructed and adapted to be moved close to end wall of the furnace thus practically closing the space above the truck 20 at this point, and the door is adapted when closed to be adjacent to the other end of the truck. It will thus be seen that the sides of the truck past which gas travels are closed and sealed against the furnace walls and the 25 combustion and heating effect in the furnace chamber will thus depend absolutely upon the mixture and the supply of the gas or oil which is delivered through the burners. Regulation may thus be effected without 30 fear of disturbance by outside conditions and much better results secured.

It is considered, unnecessary to describe the operation of the furnace as it will be evident from the foregoing description. 35 The material will first be placed upon the truck and the latter moved into position and then sealed as already described. A very much increased efficiency is secured in the present furnace and a much better treatment 40 of the materials.

Other modes of applying the principle of my invention may be employed instead of

the one explained, change being made as regards the mechanism herein disclosed, provided the means stated by any of the following claims or the equivalent of such stated means be employed.

I therefore particularly point out and distinctly claim as my invention:—

1. Sealing means for furnace chambers adapted to receive a movable car bearing material to be heated, comprising pivotally mounted bars, and complementary members on the sides of said furnace and on such cars adapted to snugly contact the sides of said bars when the same are swung, thereby sealing said furnace at the level of said bars.

2. Sealing means for furnace chambers adapted to receive a movable car bearing material to be heated, comprising pivotally mounted hollow bars, complementary members on the sides of said furnace and on such car adapted to snugly contact the sides of said bars when the same are swung, thereby sealing the furnace at the level of said bars, and means connected to the ends of said bars and adapted to supply cooling material thereto.

3. Sealing means for furnace chambers adapted to receive a movable car bearing material to be heated, comprising pivotally mounted hollow bars, complementary members on the sides of said furnace and on such car adapted to snugly contact the sides of said bars when the same are swung, thereby sealing the furnace at the level of said bars, and flexible means connected to the ends of said bars and adapted to supply cooling material thereto.

Signed by me, this 20 day of June, 1913.

FRANK C. PARSONS.
